BALL PISTON PUMP

Fritz Paulsmeier, Hamburg-Bergedorf, and Hans Warschau, Hamburg-Fuhlsbuttel, Germany

Application September 12, 1951, Serial No. 246,206

6 Claims. (Cl. 103—117)

1

The present invention relates to improvements in ball piston pumps.

An object of the invention is to provide a fluid pump of the type comprising a spherical pump chamber, a piston member having a spherical surface fitting into said pump chamber, and two operating elements positioned at right angles to each other and individually journaled to said piston member for universal movement of one operating element relative to the other operating element, the piston member and the operating elements being so shaped that losses due to internal friction of the fluid and friction between the latter and the movable parts of the pump are reduced to a minimum.

A further object of the invention is the provision of a fluid pump of the type described supra, in which the spherical surface of the piston member is only interrupted by two relatively small cut-outs for receiving the operating elements, leaving relatively large ball segments at either side of the journal portions of the operating elements affording secure connection of the latter with the piston member and reducing leakage to a minimum and considerably increasing over-all efficiency of the pump. Due to the considerable sealing surfaces and the secure universal joint connections provided in the pump according to the invention, this pump can produce extraordinarily high pressures.

Two constructional embodiments of the invention are described below with reference to the accompanying drawings wherein:

Figs. 1 to 3 show a first embodiment of the invention, Fig. 1 being a section of the pump on line I—I of Fig. 3, Fig. 2 being a section along line II—II of Fig. 1, and Fig. 3 being a section on III—III of Fig. 1.

Figs. 4 to 6 show a second embodiment, Fig. 4 being a sectional view corresponding to Fig. 1, Fig. 5 being a section on V—V of Fig. 4, and Fig. 6 being a view toward the suction side of the pump according to Fig. 4.

Fig. 7 is an exploded view of the heart of the pump according to the invention.

Fig. 8 is an exploded view as Fig. 7, the parts being revolved 90° relatively to Fig. 7.

According to Fig. 1 the driving shaft 1 is rigidly connected with an operating element 2 formed as a ball socket. This encloses in a pincer-like manner the cylindrical head of the oscillating piston 4 in the manner of a knuckle joint, piston 4 also having a guide groove 12 (see Fig. 3) extending over two thirds of its periphery. Piston 4 is carried by the operating element 2.

2

The cylindrical head of the oscillating piston 4 is rigidly associated with two ball segments 5 and 6 (see Fig. 2) and is therefore completely supported in the housing 11 which is provided with an exchangeable bearing lining 11a.

The pumping action of the machine is obtained in such manner that on rotating the driving shaft 1 the oscillating piston sections 4, 5 and 6 driven by the driving element 2 are rotated and simultaneously oscillated due to engagement of the guide groove or cut-out 12 with an operating element 3a having a pin 3 inclined to the driving shaft 1 (see Fig. 3) so that between the flanks of the elements 2 and 3a on the one hand and the flanks of the cut-outs in piston 4 on the other hand chambers are successively opened and closed with a mouth-like movement in front of the inlet and outlet openings 7 and 8.

In the embodiment according to Figs. 4 to 6 the cylindrical head is not provided on the oscillating piston 14 but on the driving element 15. Correspondingly the piston 14 is formed as a socket to receive this head. Moreover, this embodiment differs from that of Figs. 1 to 3 because the concave surface portions 16 of the driving element 15 (Fig. 4) and the flanks or surface portions 17, 17' of the other operating element 19 (Fig. 5) are not flat but concave and the bottom portions 18, 18', respectively, of the piston cut-out in 14 are correspondingly convex. Thereby the result is obtained that the fluid to be pumped flows tangentially into the suction chamber without pressure loss and is likewise delivered from the pressure chamber.

In Fig. 5 there is shown how, on the oscillating rotary movement of the pump piston 14, the inlet area Q1 in the suction chamber, beginning with the piston position according to Fig. 4, is reduced first to the area Q2 and finally to the area Q3 as shown in dotted lines. To assure that at this moment the pumped fluid can be transferred without pressure loss into the pressure chamber, the liner 20 of the bearing housing enclosing the piston is cut away at 21 on the suction side and at 22 on the pressure side (see also Fig. 4). The length of these cut-aways, which have a concave spherical configuration, depends on the diameter of the ball piston 14 and amounts to about $\frac{1}{2}$ or $\frac{1}{4}$ of the circumference of the piston.

Otherwise the construction and method of operation of the pump according to Figs. 4 and 5 are the same as that of the pump shown in Figs. 1 to 3. Due to the universal joint connection, large sealing surfaces are produced so that the pump according to the invention is suitable for

3
very high pressures, for example for spraying highly compressed fuel mixtures.

The pump may be used for several purposes because either the unloaded, idle-running shaft 3 or 3' can be used for driving other apparatus, for example a counting device for measuring the amount of fluid delivered. The vacuum on the suction side of the pump may be used for operating a milking machine. Compressed air delivered by the pump may be used for inflating vehicle tires.

The pump according to the invention can also be constructed for example as a compressor for a refrigerator.

The material for the ball socket for the operating elements 2, 15, 19 and the piston 4 or 14 can be chosen according to the type of fluid to be pumped. Besides steel, bronze, aluminum, and synthetic materials, rubber can be used. Types of rubber are known which are very strong and 20 adhere firmly to metals. Pistons, piston segments and bearing sockets made of such rubbers permit the use of the pump *inter alia* not only for pumping clear liquids but also water containing sand and other little- or non-lubricating 25 fluids whereby the field of application of the pump is considerably increased.

What we claim is:

1. A pump comprising a housing having a spherical pump chamber, an inlet and an outlet 30 conduit extending from said chamber, a member having a spherical surface and being rotatable in said chamber, said member having a first and a second cut-out, said cut-outs being diametrically opposed, each cut-out having two plane, spaced, and parallel side walls arranged symmetrically with respect to planes containing the center of said member, the side walls of the first cut-out being placed at a right angle with respect to the side walls of the second cut-out, said first cut-out 35 having a cylindrically curved, central bottom portion extending around a diameter of said member which diameter is at a right angle with respect to the planes of the side walls of said first cut-out, said first cut-out having two bottom portions symmetrically flaring from said central bottom portion between said side walls, a first operating element having two plane parallel side surfaces individually slidably engaging the plane parallel side walls of said first cut-out, said first 40 element having an outer surface portion shaped spherically with the same diameter as the spherical surface of said member, said first element having a cylindrically curved surface portion extending at a right angle with respect to said plane parallel surfaces and slidably fitting said central bottom portion of said first cut-out, said first element having two surface portions symmetrically flaring from said cylindrically curved surface portion, said second cut-out having a cylindrically curved central bottom portion extending between and at a right angle to the planes of the side walls of said second cut-out and around a diameter of said member, said second cut-out having two bottom portions symmetrically flaring from said central bottom portion of the second cut-out between said side walls to the spherical surface of said member, a second operating element having two plane parallel side surfaces individually slidably engaging the plane parallel side walls of said second cut-out, said second element having an outer surface portion shaped spherically with the same diameter as the spherical surface of said member, said second element having a cylindrically curved surface portion having the same radius as and slidably engaging said central bottom portion of said second cut-out and extending at a right angle to the side surfaces of the second element, said second element having two concave surface portions symmetrically flaring from said concave, cylindrically curved sur-

rotatable on said central bottom portion of said second cut-out, said second element having two surface portions symmetrically flaring from the cylindrically curved surface portion of the second element, and a shaft means connected with each of said elements and individually extending on the axis of symmetry of said elements.

2. A pump comprising a housing having a spherical pump chamber, an inlet and an outlet conduit extending from said chamber and being disposed on a straight line, a member having a spherical surface and being rotatable in said chamber, said member having a first and a second cut-out, said cut-outs being diametrically opposed, each cut-out having two plane, spaced, and parallel side walls arranged symmetrically with respect to planes containing the center of said member, the side walls of the first cut-out being placed at a right angle to the side walls of the second cut-out, said first cut-out having a concave, cylindrically curved bottom portion, the longitudinal axis of said bottom portion coinciding with a diameter of said member which diameter is at a right angle to the planes of the side walls of said first cut-out, said first cut-out having two convexly curved bottom portions symmetrically flaring from said concave bottom portion between said side walls to the spherical surface of said member, a first operating element having two plane parallel side surfaces individually slidably engaging the plane parallel side walls of said first cut-out, said first element having an outer surface portion shaped spherically with the same diameter as the spherical surface of said member, said first element having a convexly cylindrically curved surface portion extending at a right angle to said plane parallel surfaces and slidably fitting into the concave cylindrically curved bottom portion of said first cut-out of said member, the circumferential extension of said convex surface portion being greater than the cylindrical extension of said concave bottom portion, said first element having two substantially concave surface portions symmetrically extending from said convex surface portion and individually substantially conforming with the convexly curved bottom portions of said member, the angle enclosed by said concave surface portions being smaller than the angle enclosed by said convexly curved bottom portions of the first cut-out, affording oscillation of said member relatively to said first element about the longitudinal axis of said convex bottom portion, said second cut-out having a convexly cylindrically curved central bottom portion extending between and at a right angle to the planes of the side walls of said second cut-out and around a diameter of said member, said second cut-out having two convexly curved bottom portions symmetrically flaring from said central bottom portion of the second cut-out between said side walls to the spherical surface of said member, a second operating element having two plane parallel side surfaces individually slidably engaging the plane parallel side walls of said second cut-out, said second element having an outer surface portion shaped spherically with the same diameter as the spherical surface of said member, said second element having a concave cylindrically curved surface portion having the same radius as and slidably engaging said central bottom portion of said second cut-out and extending at a right angle to the side surfaces of the second element, said second element having two concave surface portions symmetrically flaring from said concave, cylindrically curved sur-

face portion of the second element and individually substantially conforming with the convexly curved bottom portions of said second cut-out, the angle enclosed by said flaring surface portions of said second element being smaller than the angle enclosed by said convexly curved bottom portions of said second cut-out, affording oscillation of said member relating to said second element about the longitudinal axis of the central bottom portion of the second cut-out, and individual shaft means individually connected with each of said elements and extending radially of said member.

3. A pump as set forth in claim 2, the outer part of said symmetrical concave surface portions of said first element extending in a direction substantially parallel to the line on which said conduits are disposed.

4. A pump as set forth in claim 2, said concave flaring surface portions of said elements individually extending at a right angle to the parallel side surfaces of the respective elements.

5. A pump as set forth in claim 2, the shaft

5

10

means connected with said first element extending at a right angle to the line on which said conduits are disposed, said inlet conduit having an interior wall portion adjacent to said first element, and a cut-away in said wall portion.

6. A pump as set forth in claim 2, comprising a cut-away in each of said conduits adjacent to the pump chamber, said cut-aways being disposed on a diameter of the pump chamber.
